UNITED STATES PATENT OFFICE

SIDNEY A. MILLER, OF HUNTINGTON BEACH, CALIFORNIA

COMBINATION CARRIER AND GRIP

Application filed September 7, 1927. Serial No. 217,979.

This invention relates to oil pumping apparatus, and particularly to the grip used to connect the polish rod with the cables or reins of the walking beam or other pump actuating mechanism. It will be recognized, however, that in many of its aspects, the invention is not limited to apparatus of that particular type, but is generally applicable to well drilling equipment of various types, and to many pipe holding devices.

A general object of the invention is to provide an improved polish rod grip which functions automatically to clamp the rod with unusual force and eliminates all danger of slippage between the parts during operation. The gripping action is accomplished by slips surrounding the rod and mounted in a novel manner, provision being made for locking the slips in a non-clamping position to permit adjustment of the polish rod and associated parts. The slips are retained in clamping position automatically, and the gripping action is obtained without the aid of tightening bolts and nuts such as characterized prior constructions.

A feature of the invention consists in forming the grip and rod carrier in a unitary structure, thereby simplifying the spacing and adjustment of the pump plunger, and rendering it possible for one man to perform such adjustments.

These and other features of the invention will appear more fully from the following detailed description when read in connection with the accompanying drawings, and will be pointed out in the appended claims.

In the drawings,

Fig. 1 is a side elevation of the combined carrier and grip embodying the features of the invention;

Fig. 2 is a vertical section showing the grip in released position;

Fig. 3 is a plan view, portion of the carrier being broken away;

Fig. 4 is a vertical section taken at right angles to Fig. 2, and illustrates the grip in clamping position;

Fig. 5 is a horizontal section on lines 5—5 of Fig. 4; and

Fig. 6 is a side elevation of the grip.

The polish rod carrier is indicated generally at 2 and consists of a heavy bar 4 substantially rectangular in cross section, and provided at each end with a circular trunnion 6. These trunnions carry bearing members (not shown) which form a part of the cables leading to the walking beam. The operation of the carrier from the walking beam will be readily understood by those skilled in the oil pumping industry.

Intermediate its ends, the carrier beam is provided with an opening 8 for receiving the usual polish rod 10. As illustrated, the opening is conical in shape, the sides tapering gradually inwardly from top to bottom, and the smallest diameter at the lower end being greater than that of the polish rod so as to freely receive the latter.

Rising from the upper face of the carrier, and on opposite sides of the opening 8, are spaced brackets 12, connected at the upper end by a cross member 14 having an opening 16 centrally located therein, and directly above the opening in the carrier. Within the opening 16 in the cross member is mounted a bushing 18 having annular flanges 20 and 22 extending from its upper and lower faces, respectively. To facilitate the assembly of the various parts, the bushing 18 is preferably formed as a separate unit and detachably connected to the supporting cross member, as, for example, by screws 24.

A gripping element 26 is slidably mounted within the bushing. The gripping element consists of a hollow cylindrical body 28 in external diameter slightly smaller than the opening in the bushing, so as to snugly fit therein and capable of a free sliding movement. The lower end of the body terminates in an enlarged conical head 30, the outer side walls of which are tapered to substantially the same degree as the opening 8 in the main carrier bar. The lower portion of the body and the conical head of the gripping element are slit at a plurality of spaced points as 32, thereby dividing the element into elongated sectors 34 which form gripping slips. The interior passage through the body 28 and head 30 is slightly larger than the polish rod and ordinarily the latter

would be able to slide therein. When the head of the gripping element is lowered into the opening in the carrier, the internal passage will be reduced by the movement of the slips inward toward each other, this movement being produced by the coaction of the tapered walls of the slips and carrier opening. The farther the head is shoved into the carrier opening, the greater the inward movement of the slips, and the smaller the passage becomes. As a consequence, the polish rod is gripped between the slips with increased force as the head moves downward.

The invention contemplates that the lower or gripping position of the head 30 should be the normal one, and to this end a heavy spring 36 surrounds the lower portion of the gripping element, this spring being confined between the bushing 18 and the head 30. The flange 22 on the bottom of the bushing serves to guide the upper coils of the spring. During the normal pumping operation, the gripping element is at all times urged downward by the spring, thus forcing the slips into rod clamping position.

The mechanism for elevating the gripping element against the action of spring 36 to release the polish rod will now be described. A second spring 38 surrounds the upper portion of the gripping element and is confined between the upper face of bushing 18 and a flange 40 formed on the upper end of the gripping element, the bottom of the spring being guided by the annular flange 20 previously described as formed on the bushing. The upper spring is much weaker than the lower spring, and, in practice, is just made of such strength to readily carry the weight of the gripping element. The function of the upper spring is to elevate the grip when the lower spring has been rendered inactive.

The lower spring 36 is supported by a ring 42 which normally is seated on the shoulder 44 formed between the body and head of the gripping element. The ring is provided with projecting lugs 46 at diametrically opposed points, these lugs being engaged in slots 48 formed in the arms 50 of a U-shaped yoke 52. The yoke is connected to and is actuated by an operating handle 54 which extends through a recess 56 provided in one of the side brackets 12. The bracket forms the fulcrum for the handle and, to facilitate operation, the handle and inner edge of the recess may be similarly curved as at 58 to obtain a smooth rocking action. When the outer end of the handle is depressed, the ring 42 will be elevated and, by compressing the lower spring, the downward pressure against the gripping element is relieved. Immediately the upper spring begins to function and raises the gripping element into the position indicated in Figs. 1 and 2, wherein the slips are out of contact with the carrier opening, and consequently no longer bind the polish rod. The carrier or rod, or

both, being thus released, may then be moved to any position of relative adjustment required. To hold the grip in released position, the handle may be locked in its depressed position in any preferred manner, such for example, as by a hook 60 attached to the carrier.

Proper adjustments having been made, the handle is disengaged from the retaining hook, and the lower spring immediately forces the gripping element downward, the head lowering into the opening in the carrier body. After the tapered sides of the grip head have contacted with the walls of the carrier opening, further downward movement causes the slips to move inward against the polish rod, thereby locking the latter to the carrier. It should be noted that the gripping action of the slips is not entirely dependent upon the force of spring 36, or any other mechanical means, the polish rod itself constantly acting to pull the slips downward. Necessarily the heavier the weight applied to the polish rod, the greater the binding action between the rod and the slips becomes. Practically all danger of slippage is thus avoided.

Since the manner in which the different parts of the device operate to perform their function has been set forth in connection with the detailed description thereof, no further description of the operation is necessary for an understanding of the invention.

Having described the invention, what I claim as new and desire to secure by Letters Patent of the United States is:

1. A device of the character described, having in combination, a carrier adapted to be attached to the walking beam of an oil pump, a bushing mounted on said carrier and in spaced relation thereto, a polish rod grip slidably mounted in said bushing, the said grip including a plurality of slips adapted to surround the polish rod, yielding means for constantly urging the grip to assume a position in which the slip will clamp the rod, means for rendering said yielding means inactive, and means for moving the grip into non-clamping position.

2. A device of the character described, having in combination, a carrier adapted to be attached to the walking beam of an oil pump, the said carrier having a conical opening therein adapted to receive the polish rod, a bushing mounted on said carrier and in spaced relation thereto, a polish rod grip slidably mounted in said bushing, the said grip including a plurality of slips adapted to surround the polish rod, the said slips being adapted to enter the opening in the carrier, means for urging the slips into said opening and causing the slips to move inwardly to grip the polish rod, means for moving the slips away from said opening to release the polish rod, and means for rendering said first mentioned means inactive.

3. A device of the character described, hav-

ing in combination, a carrier adapted to be attached to the walking beam of an oil pump, the said carrier having a conical opening adapted to receive the polish rod, a bearing mounted on said carrier and in spaced relation thereto, a bushing detachably mounted in said bearing, a polish rod grip slidably mounted in said bushing, the said grip including a cylindrical body portion and a conical head, said head being divided into a plurality of slips, the said head being adapted to enter the conical opening of the carrier and cause the slips to move inwardly and grip the polish rod, a spring for urging the grip into clamping position, means for rendering said spring inactive, and a spring for moving the grip into non-clamping position when the first mentioned spring is inactive.

4. In a device of the character described, the combination of a body having a socket, of a bushing rigidly secured to said body in spaced relation thereto, a rod grip having one end projecting into said socket and the opposite end projecting into said bushing, means normally forcing the rod grip toward the socket into gripping position, and means for moving the rod grip toward the bushing.

5. A device of the character described, having in combination a carrier adapted to be attached to the walking beam of an oil pump or the like, said carrier having a tapered socket therein a bushing mounted on said carrier in spaced relation thereto, a rod grip slidably mounted in said bushing, said grip having slips slideable in said socket yielding means for normally urging the grip to assume a position in which the grip will clamp the rod, and means for moving the grip into non-clamping position.

6. A device of the character described having, in combination, a carrier adapted to be attached to the walking beam of an oil pump, a polish rod grip mounted on said carrier and movable therewith, the said grip being mounted for relative movement with respect to the carrier, means normally urging the grip into clamping position, means normally urging the grip into non-clamping position and additional means for rendering said first named means inactive.

7. A device of the character described having, in combination, a carrier adapted to be attached to the walking beam of an oil pump, a polish rod grip mounted on said carrier and movable therewith, the said grip being mounted for relative movement with respect to the carrier, means normally urging the grip into clamping position, means normally urging the grip into non-clamping position, additional means for rendering said first-named means inactive, and means for locking said first-named means in inactive position.
